UNITED STATES PATENT OFFICE.

ALBERT L. RICE, OF WHEELING, WEST VIRGINIA.

MODE OF SEPARATING EMBROIDERIES.

SPECIFICATION forming part of Letters Patent No. 307,801, dated November 11, 1884.

Application filed September 8, 1883. (No specimens.)

To all whom it may concern:

Be it known that I, ALBERT L. RICE, a resident of Wheeling, in the county of Ohio and State of West Virginia, have invented certain new and useful Improvements in Dress Trimmings; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention is an improvement upon Letters Patent No. 266,525, granted to me October 24, 1882, relating to the class of textile fabrics known as "embroideries, edgings, and insertings." In said patent the rows of embroidery were rendered capable of being easily separated or torn apart by means of a line of perforations between the rows, which weakened the goods so one portion could easily be torn from the other, in the manner of a sheet of postage-stamps.

The present invention consists of ruling the goods between the rows, either in a straight line or by a line following the contour or outline of the edge of the embroidery, with a fluid or ink composed of disintegrating substances that will operate to partially destroy the fabric where it comes in contact with the same; then in neutralizing or volatilizing the acid to prevent subsequent injury to the goods outside of the line, whereby the rows of embroidery can readily be torn from the roll or separated one from the other, as desired, without liability of tearing or otherwise injuring the same.

In the drawings, Figures 1 and 2 represent bolts of embroidery.

The letters A designate the rows of embroidery; B, the ruling, (shown by a broad black line,) following the contour or outline of the edge of the embroidery; C, the ruling, running straight between the rows and parallel with them.

I propose to rule the goods with the disintegrating fluid by means of ruling-pens in a suitable frame, similar to that employed in ruling writing-paper. In the case of edgings, or where compound curved lines are necessary,

they can be ruled by means of rotary inking wheels or stencils.

To rule the goods with a fluid that will eat away the fabric along the line of contact, it becomes necessary that the chemical employed should be one that can be neutralized or exhausted immediately after contact, to prevent future injury to the goods; and to accomplish this I use a destructive fluid or ink composed of sulphuric acid 66° one part, water two parts; the acid diluted with one part water, starch sufficient to make thick, mixed with one part water, and the acid and starch combined. To this mixture is added sufficient gum-arabic to give it the proper consistency to run freely from the ruling-instruments, the proportions being changed to suit the class of goods upon which it is intended to be used and the ruling devices employed to apply it to the cloth.

Immediately after the fluid is applied the goods are passed over or between heated rollers or plates, which operate to neutralize or exhaust the acid in the fluid and prevent it from spreading, thereby leaving a clear and distinct black line along the cloth, showing where the rows of embroidery can be separated from each other. After this operation the goods are folded into bolts in the usual manner, and are ready to be placed on the market.

There are various other methods for neutralizing or exhausting the acid after it has produced the desired effect upon the line. One neutralizing method consists in the use of an alkali, either by immersing the line in a solution of alkali or by running a line of caustic or other suitable alkali over the acid line; but, perhaps, the most practical method is by volatilizing the acid by heat immediately after it has been applied to the goods, as before stated. I do not wish to limit this last step in my invention to any one of the foregoing methods, as either can be employed for exhausting the acid without departing from the spirit of the invention. Separating the rows in this way is especially serviceable in edgings which have a scallop or irregular edge, for it saves the labor of cutting around the edge by hand to remove the surplus material. In some cases the bolt of goods can have a

straight line of ruling between the rows of embroidery, and also have a line following the pattern or scallop on the edge of the embroidery, so that one row can be separated from the 5 other on either line, and the surplus cloth removed from the edge.

The principal advantage of this mode of preparing the goods so the rows of embroidery can be easily separated or removed from the 10 bolt by ruling separating-lines with a disintegrating chemical fluid is, that the goods tear asunder or apart without injury, as the line of separation is uniform and regular, which is not the case where the goods are perforated, 15 for frequently some of the threads are not cut away at all, and the result is that the rows tear across instead of lengthwise of the goods.

It is obvious that other acids or chemical compounds could be devised to accomplish the 20 same result, and such I consider within the scope of my invention.

Having described my invention, what I claim and desire to secure by Letters Patent of the United States, is—

The method herein specified of separating 25 fabrics on any desired line, which consists, first, in ruling the goods on the separating-line with a disintegrating-acid, whereby the fabric on the line is partially destroyed, then in arresting the further chemical effect of the 30 acid, substantially as described, and for the purposes set forth.

In testimony that I do claim the foregoing as my own I hereby affix my signature in presence of two witnesses.

ALBERT L. RICE.
